UNITED STATES PATENT OFFICE.

HORACE BEARD, OF WILTON, NEW HAMPSHIRE.

ANTI-RATTLER FOR THILL-COUPINGS.

SPECIFICATION forming part of Letters Patent No. 247,739, dated October 4, 1881.

Application filed July 28, 1881. (No model.)

To all whom it may concern:

Be it known that I, HORACE BEARD, of Wilton, of the county of Hillsborough and State of New Hampshire, have invented a new and useful Improvement in Anti-Rattling Devices for Thill-Couplings; and I do hereby declare the same to be described in the following specification and represented in the accompanying drawings, of which—

10 Figure 1 denotes an edge view, Fig. 2, a rear elevation, and Fig. 3 a vertical section, of a spring and its supporter constructed and combined in accordance with my invention. Fig. 4 is a side view of a thill-coupling with one of 15 my improved springs and supporters applied thereto.

The invention has reference to that for which Letters Patent No. 196,554, dated October 30, 1877, were granted to me. The patented article while in use is liable to become broken 20 when the thill is turned backward forcibly against it, so as to crowd and compress it against the clip.

The object of my improvement is to prevent 25 such an accident. This is accomplished by employing with the spring a supporter to be fixed to and project upward within it, and, with the spring, to be formed substantially as represented in the accompanying drawings, in which 30 A denotes a thill, and B the clip, with which it is coupled in the usual manner.

The anti-rattling spring is shown at C as 35 formed of a strip or piece of plate metal of proper width, bent in manner as represented. Near its front end it is fastened by rivets *a* or other suitable means, to a support-piece or supporter D, shaped essentially and extended upward within the spring in the manner shown, the supporter being provided with a curved 40 arcal recess, *b*, to fit to and receive the cylindrical part *p* of the thill-coupling. The supporter at its upper part is provided with an eye, *e*, entirely or partially through it, the said eye being to enable a person, by means of a hook 45 or other suitable appliance inserted into it, to withdraw the spring and supporter from the

thill-coupling. The free part of the spring is shown in Fig. 2 as tapering or reduced in width. This renders it more flexible, and enables one to insert it more easily into the thill-coupling. 50

From the above it will be seen that, with the supporter made, arranged, and combined with the spring in the manner substantially as represented, the spring cannot easily become broken in its upper part, or bend, or at any other point when compressed between the clip and the thill, on the latter being forcibly turned upward and backward against the spring. 55

I do not herein claim a spring formed in one piece of metal and recessed in the manner described and represented in the Patent No. 196,554, hereinbefore referred to. Nor do I claim a thill-coupling anti-rattling device composed of a spring and a block of india-rubber, shaped and arranged as represented in the 65 United States Patent No. 196,377, for in my device the spring-supporter is of metal and inelastic, and besides is recessed to bear directly against the cylindrical part *p* of the coupling, and extends above the joint of the coupling 70 and into the part of the spring, which is above such joint, and thereby operates to prevent such part from becoming crushed when the thill is turned up. Furthermore, my device has no shoulder to prevent it from being withdrawn upward from the coupling. 75

What I claim as my present invention is as follows:

1. The combination of the bent spring C, with its inelastic supporter D, recessed in its 80 front and fastened to and extended upward within the part of the spring that projects or is to project above the coupling-joint, all being substantially as set forth.

2. The spring-supporter D, recessed on its 85 front, and inelastic, and combined and arranged with the spring C, and provided with the eye *e*, as and for the purpose explained.

HORACE BEARD.

Witnesses:

ALBERT BEARD,
MOSES CLARK.
